UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

TYPE-WRITING MACHINE.

1,273,302.

Specification of Letters Patent. Patented July 23, 1918.

Original application filed June 29, 1910, Serial No. 569,502. Divided and this application filed September 1, 1917. Serial No. 189,255.

To all whom it may concern:

Be it known that I, WALTER WRIGHT, a citizen of the United States, residing in New York, in the county of New York and State 5 of New York, have invented certain new and useful Improvements in Type-Writing Machines, of which the following is a specification.

This invention relates to an improvement 10 in typewriting machines, and more particularly to a mechanism for shifting a polychrome or a bichrome-ribbon mechanism both automatically, to correspond with the travel of the carriage, and manually. This 15 case is a division of my application, Serial No. 569,502, filed June 29, 1910.

An automatic control is provided for changing the ribbon-shifting mechanism so as to print red and black, at different intervals, corresponding to different typewriting columns or zones, as determined by the carriage. This mechanism is driven at the same time that the carriage is driven from a train of gearing driven by a motor. The 25 automatic control of the ribbon-shifting mechanism may be thrown out of action or silenced by shifting a cam, which moves an operating cam vertically out of register with its follower. Then the bichrome ribbon-shifting mechanism can be controlled manually, to enable the printing of characters, either red or black.

Other features and advantages will hereinafter appear.

35 In the accompanying drawings,

Figure 1 is a vertical section, taken from front to rear, with parts omitted to simplify the showing.

Fig. 2 is a rear view, in elevation, showing the train of gearing from the motor to the carriage and to the automatic control for the ribbon-shifting mechanism.

Fig. 3 is a skeleton perspective view, showing the connection from the automatic control and the hand control to the ribbon-shifting mechanism.

Fig. 4 is a detail section, showing a lost-motion connection between the shaft, which operates the ribbon-shifting mechanism, and 50 the hand-crank or manual control for operating the same. This view shows the shaft in the position corresponding to the printing of black characters.

Fig. 5 is a view similar to Fig. 4, except that the shaft is shifted to print red characters. 55

Fig. 6 is a detail vertical section of the cam of the automatic control, showing the same lowered to an inactive position, and out of active register with the follower. 60

Fig. 7 is a top plan view of the parts shown in Fig. 6, showing in full lines the parts in the same relation as in Fig. 6, and in dotted lines the outer position of the follower with the cylindrical cam raised and 65 the follower riding on the latter.

Referring more particularly to the separate parts of the invention, as embodied in the form shown in the drawings, character keys 1 depress key levers 2 to rock bell 70 cranks 3, so as to swing type-bars 4 up rearwardly against the front side of a platen 5 mounted to rotate on a carriage 6. The carriage 6 may be advanced step by step under the control of an escapement mechanism, indicated in general at 7. This escapement mechanism is the same as is found in the standard Underwood typewriting machine; and includes a rack bar 8 pivotally mounted on the carriage 6, and meshing with 75 a pinion 9 connected by a one-way pawl-and-ratchet mechanism 9^a to an escapement wheel 10. The escapement wheel 10 is controlled in its rotation by a fixed dog 11 and a loose dog 12 mounted on a rocker 13. The 80 rocker 13 is actuated each time a character key 1 is depressed, by means of a universal frame 14. The frame 14 is in turn operated by a heel 15 carried by each of the type-bars 4. The universal frame 14 returns with 85 the return of the type-bars 4, as the character keys 1 return to their normal positions. 90 This is done by means of a spring 16 acting on the universal frame 14.

The type-bars 4 print on the work-sheet 95 carried by the carriage 6 indirectly through a ribbon 17, which may be polychrome and which is interposed between the types 18 and 19 on the type-bars 4 and the work-sheet on the platen 5. In the present case, the ribbon 17 is shown to be a bichrome ribbon having its upper half black, as indicated at 20, and its lower half red, as indicated at 21. The ribbon 17 is threaded through a vibrator 22, which is raised at the 100 operation of each of the character keys 1 105

to interpose the ribbon 17 between the types 18 and 19 and the work-sheet carried by the platen 5.

The ribbon 17 is raised a greater or less amount, according to whether it is desired to print red or black. For this purpose, the vibrator 22 is operated by a bell-crank 23, which includes one arm comprising a hook 24 connected directly to the shank of the vibrator 22. Another arm 25 of the bell-crank 23 has a pair of studs 26 and 27, projecting from opposite sides thereof at different distances from the pivot of the bell-crank 23. The studs 26 and 27 are engaged and operated alternately by a pair of flanges 28 and 29 forming part of a shift 30. The shift 30 is mounted on the universal frame 14 and vibrates back and forth with the latter at the actuation of the character keys 1, so as to raise and lower the ribbon 17 a greater or, less amount, depending upon whether the stud 27 is in engagement with the flange 29 or the stud 26 is in engagement with the flange 28. The shift 30 has a pin-and-slot connection 31 with the universal frame 14, to permit of a relative shifting movement.

The flanges 28 and 29 have vertical slots 32 and 33, whereby the shift 30 may be positively connected alternatively with either the stud 26 or the stud 27. For printing red characters, the parts are in the position of Fig. 3, with the stud 27 in the slot 33, so that the vibrator 22 is swung upwardly at the actuation of any of the character keys 1 to the maximum distance, so as to bring the lower red section 21 of the ribbon 17 between the types 18 and 19 and the platen 5. For printing black characters, the shift 30 is slid in the opposite direction, so as to bring the flange 28 into active connection with the stud 26, whereby the vibrator 22 will be swung the minimum distance, so as to bring the upper black section 20 of the ribbon 17 between the types 18 and 19 and the platen 5.

The shift 30 is adjusted sidewise for printing black or red, by means of a link 34, which, in turn, is operated by an arm 35 secured to the rock shaft 36. The rock shaft 36 may be operated manually by means of a hand-crank 37, so as to determine whether the printing shall be red or black. The hand-crank 37 may be locked in its adjusted position by means of a detent 38, and has a lost-motion connection 39 with the shaft 36, so that the shaft 36 may be otherwise operated to change the color of printing without disturbing the hand-crank 37.

As explained in the parent case, if it was desirable to print black in certain computing zones or major columns, and in other computing zones or major columns to print red, the change from printing black to red, and vice versa, was done automatically un-

der the control of means driven in synchronism with the typewriter carriage. For this purpose, the rock-shaft 36, which controls the position of the shift 30 is operated from a source other than the hand-crank 37. This includes an arm 40 secured to the rock shaft 36 and operated by a link 41 against the tension of a spring 42. The link 41 is guided in its movement by extending in an opening through a bracket 43, and is limited in its movement by means of a collar 44 secured to the link 41 and engaging the bracket 43. The link 41 is operated by an arm 45 secured to a shaft 46, which, in turn, is operated by a follower 47. The follower 47 is operated by a cam 48 secured to the vertical shaft 49.

The shaft 49 is rotated in synchronism with the carriage 6, so that its movements will keep pace with the movements of the carriage from zone to zone. For this purpose, the carriage 6 is provided with a rack 50 engaged by a gear 51. The gear 51 is secured to a shaft 52 which may be driven from a motor 53 by means of a train of gearing including a bevel gear 54, secured to the vertical shaft 52 and meshing with a bevel gear 55, secured to a horizontal shaft 56, which, in turn, is connected to the motor shaft by means of a pair of intermeshing bevel gears 57 and 58, secured, respectively, to the motor shaft and the shaft 56.

The shaft 52 is connected to the cam shaft 49 by means of a train of gearing including a bevel gear 59 secured to the shaft 52 and meshing with a bevel gear 60 secured to a shaft 61. The shaft 61 is provided with a bevel gear 62, which meshes with a bevel gear 63 secured to a shaft 64. The shaft 64 is provided with a gear 65 meshing with a gear 66 secured on the cam shaft 49. The train of gearing between the carriage 6 and the cam shaft 49 is such that the cam shaft 49 will make a complete revolution for one run of the carriage 6 from end to end of its travel. Thus, the cam 48 can be so arranged as to control the change in the color of printing to correspond with the different computing zones or major columns, as determined by the travel of the carriage 6, according to a prearranged plan.

The cam 48 may have one or more outer rises or levels 67, which, when the follower 47 rests thereon, control the position of the part shown in Fig. 3, with the stud 27 in engagement with the flange 29, giving a maximum swing to the ribbon 17, so that the lower strip 21 will come between the types 18 and 19 and the work-sheet carried by the platen 5. On the same horizontal plane as the cam rise 67, there may be provided one or more depressed sections 68 nearer the axis of the shaft 49, which correspond to the position of the shift 30 to the right of that shown in Fig. 6, which permits

the flange 28 to be connected to the stud 26, so as to give a minimum vibration to the ribbon 17, causing the upper strip 20 of the ribbon 17 to be interposed between the types 5 18 and 19 and the work-sheet on the platen 5.

The cam 48 has a cylindrical portion 69, corresponding to the inner level 68, which, when the follower 47 is in register with the same, renders the cam 48 incapable of 10 moving the follower 47, and thus incapable of controlling the shift 30. This silences the automatic control of the color of printing, but a change can be made by means of the hand-crank 37, as explained above. To 15 shift the cam 48 vertically, and thus determine its active and inactive positions, the shaft 49 is adjustable vertically. For this purpose, the shaft 49 is provided with a collar 70, which rests on a cam 71 secured 20 to a rock shaft 72. The rock shaft 72 is operated by a lever 73, which, when in the position of Fig. 2, holds the rotatable shaft 49 and the cam 48 in their raised active position. When the lever 73 is swung down, 25 the control shaft 49 and the cam 48 are lowered to their inactive positions.

The operation of the device will be readily understood when taken in connection with the above description. The cam 30 48 is formed with one or more rises 67 and one or more depressed sections 68, according to a prearranged plan of colors of printing desired in the several zones or major columns, as determined by the travel 35 of the carriage 6. When it is desired to control automatically a change in the color or character of the printing to correspond with the different zones automatically, the lever 73 is placed in the Fig. 2 position with the 40 cam 48 raised so as to be capable of operating the follower 47 against the tension of the spring 42, and thus determines the position of the shift 30. The position of the shift 30, in turn, determines the stroke 45 of the vibrator 22 at each operation of one of the character keys 1, since the rotary position of the shaft 49, and thus the cam 48 is controlled in synchronism with the position of the carriage 6 by the interconnecting 50 trains of gearing. The rises 67 and depressed portions 68 will determine the color of printing to correspond with the successive zonal position of the carriage 6. When the follower is in engagement with the 55 raised portion 67, then the shift 30 will be in the Fig. 3 position, corresponding to a maximum movement of the vibrator 22, so as to interpose the lower red section of the ribbon 21 between the types 18 and 19 and 60 the work-sheet carried by the platen 5. When the control shaft 49 is rotated to such a position that a depressed portion 68 thereof is in register with the follower 47, then the shift 30 will be adjusted to the 65 opposite extreme of its movement, so as

to cause a minimum vibration of the ribbon 17, thus interposing the upper black section 20 of the ribbon 17 between the types 18 and 19 and the work-sheet carried by the platen 5.

The automatic control of color printing can be silenced by shifting the lever 73 to a horizontal position, which will lower the shaft 49 and the cam 48, so as to bring the continuous cylindrical portion 69 of the cam 48 in register with the follower 47. The automatic control can then rotate idly without operating the follower 47, and, thus, without changing the position of the bichrome ribbon-shifting mechanism. Under such circumstances, if it is desired to change from printing one color to printing with the other color, the shifting mechanism can be adjusted by the hand-crank 37. Normally, the hand-crank 37 is in the position of Fig. 3, and is yieldingly locked in this position by the detent 38. The automatic control can operate the bichrome-shifting mechanism without changing the 80 position of the hand-crank 37, so that when the automatic control is silenced the spring 42 will return the same to a normal position, corresponding to the position of the hand-crank 37; the lost-motion provided by the pin-and-slot or lost-motion connection 39 permits the automatic control to rock the shaft 36 without disturbing the hand-crank 37.

Variations may be resorted to within the scope of the invention, and portions of the 100 improvements may be used without others.

Having thus described my invention, I claim:

1. The combination with a platen and a carriage, of a polychrome ribbon mechanism coöperating with said platen to enable the printing in two colors, and a rotary automatic control for said polychrome ribbon mechanism connected to the carriage and arranged to shift the same according to a 110 pre-arranged plan to print in a plurality of colors.

2. The combination with a platen and a carriage, of type-actions coöperating with said platen, a polychrome ribbon mechanism, 115 coöperating with said carriage and said type-actions to print selectively in any one of a plurality of colors, a manual control for said polychrome ribbon mechanism arranged to shift the same, so as to select the 120 color of printing, and a rotary automatic control connected with the carriage for shifting said polychrome mechanism to determine the color of printing.

3. The combination with a traveling carriage, of a platen mounted on said carriage, type-actions coöperating with said platen to print, a polychrome ribbon mechanism coöperating with said platen and said type-actions to enable the printing in any one of 130

a plurality of colors, and an automatic rotary shift for said polychrome ribbon mechanism controlled from said carriage, so as to enable the printing according to a pre-arranged plan in any one of a plurality of colors according to the position of said carriage.

4. The combination with a traveling carriage, of a platen on said carriage, type-actions coöperating with said platen to print, a polychrome ribbon mechanism coöperating with said platen and said type-actions to print in any one of a plurality of colors, a rotary automatic control for shifting said polychrome ribbon mechanism to print in any one of a plurality of colors and a driving train for rotating said automatic control from said carriage, so as to make the action of said automatic control correspond with the position of said carriage.

5. The combination with a platen, of a polychrome ribbon mechanism coöperating with said platen to enable the printing in any one of a plurality of colors, a manual control for selectively shifting said polychrome ribbon mechanism to determine the color of printing, a rotary automatic control for shifting said ribbon mechanism according to a pre-arranged plan, and means for silencing said automatic control.

6. The combination with a traveling carriage, of a platen mounted on said carriage, a polychrome ribbon mechanism coöperating with said platen to enable printing in any one of a plurality of colors, a rotary automatic control for shifting said polychrome ribbon mechanism to determine the color of printing, driving connections for rotating said automatic control in synchronism with the traveling movements of said carriage, a manual control for said polychrome ribbon mechanism, and means for silencing said automatic control while maintaining the same in synchronism with the movements of said carriage.

7. The combination with a platen, of a polychrome ribbon mechanism coöperating with said platen to enable the printing in any one of a plurality of colors, a linkage connected to shift said polychrome ribbon mechanism, a follower connected to operate said linkage, and a rotary cam connected to operate said follower.

8. The combination with a platen, of a polychrome ribbon mechanism coöperating with said platen to enable the printing in any one of a plurality of colors, a linkage connected to shift said polychrome ribbon mechanism, a follower connected to operate said linkage, a rotary cam connected to operate said follower, said cam comprising one or more rises and depressions determining different colors of printing and a cylindrical inactive portion determining the silencing of said cam with respect to said polychrome

ribbon mechanism, and means for shifting said cam axially to render the same active and inactive.

9. The combination with a platen, of a polychrome ribbon mechanism coöperating with said platen to enable the printing in any one of a plurality of colors, a link connected to shift said polychrome ribbon mechanism to determine the color of printing, a rock-shaft connected to operate said link, a hand-crank for manually operating said rock-shaft, an arm connected to operate said rock-shaft, a link connected to operate said arm, a follower connected to operate said link, a rotary cam connected to operate said follower, and a spring opposing the action of said cam.

10. The combination with a platen, of a polychrome ribbon mechanism coöperating with said platen to enable printing in any one of a plurality of colors, an automatic control for shifting said polychrome ribbon mechanism according to a pre-arranged plan, so as to give a predetermined sequence of colored printings, and a manual control for said polychrome mechanism having a lost-motion connection, enabling the shifting of said polychrome ribbon mechanism by said automatic control independently of a movement of said manual control.

11. The combination with a platen and a carriage, of a polychrome ribbon mechanism coöperating with said platen to enable printing in a plurality of colors, and an automatic control for said polychrome ribbon mechanism connected with the carriage and arranged to shift the same according to a pre-arranged plan to print in a plurality of colors whether the carriage is advancing or returning.

12. The combination with a platen and a carriage, of a polychrome ribbon mechanism coöperating with said platen to enable printing in a plurality of colors, an automatic control for said polychrome ribbon mechanism connected with the carriage and arranged to shift the same according to a pre-arranged plan to print in a plurality of colors whether the carriage is advancing or returning, said automatic control being releasable, and a manual control for said polychrome ribbon mechanism to shift the same so as to select the color of printing.

13. The combination with a traveling carriage, of a platen mounted on said carriage, type-actions coöperating with said platen to print, a polychrome ribbon mechanism coöperating with said platen and said type-actions to enable the printing in any one of a plurality of colors, and an automatic shift for said polychrome ribbon mechanism controlled from said carriage during both the advance and return runs of said carriage, so as to enable the printing according to a pre-arranged plan in any one

of a plurality of colors according to the position of said carriage and regardless of how said position is reached.

14. The combination with a traveling carriage, of a platen mounted on said carriage, type-actions coöperating with said platen to print, a polychrome ribbon mechanism coöperating with said platen and said type-actions to enable the printing in any one of 10 a plurality of colors, an automatic shift for said polychrome ribbon mechanism controlled from said carriage during both the advance and return runs of said carriage, so as to enable the printing according to a 15 pre-arranged plan in any one of a plurality of colors according to the position of said carriage and regardless of how said position is reached, means for releasing the ribbon mechanism at will from the control of said 20 carriage, and manually operable means for varying the operation of the polychrome ribbon mechanism.

15. The combination with a typewriter carriage and types, of a polychrome mechanism to coöperate with the types to enable 25 printing in any one of a plurality of colors, means for shifting said polychrome mechanism to different conditions, and means connected to said carriage for operating said 30 shifting means with the same color effect during both the advance and return of the carriage.

16. The combination with a typewriter carriage and types, of a polychrome mechanism to coöperate with the types to enable 35

printing in any one of a plurality of colors, means for shifting said polychrome mechanism to different conditions, and a controller driven by said carriage during both the advance and return strokes thereof, said 40 polychrome-shifting means constructed to be engaged by said controller at the same places during the return of the carriage as during the advance thereof, to have the same effect upon the polychrome mechanism 45 when the carriage is returning as when it is advancing.

17. The combination with a type-writer carriage and types, of a polychrome mechanism to coöperate with the types to enable 50 printing in any one of a plurality of colors, means for shifting said polychrome mechanism to different conditions, a controller driven by said carriage during both the advance and return strokes thereof, said polychrome-shifting means constructed to be engaged by said controller at the same places 55 during the return of the carriage as during the advance thereof, to have the same effect upon the polychrome mechanism when 60 the carriage is returning as when it is advancing, means to release the polychrome-shifting mechanism from the control of said carriage, and a manually operable device for shifting the polychrome mechanism.

WALTER WRIGHT.
